UNITED STATES PATENT OFFICE.

LIONEL H. N. LOUPRET, OF LOWELL, MASSACHUSETTS.

MAGNETO.

1,231,919.

Specification of Letters Patent. Patented July 3, 1917.

Application filed February 1, 1915. Serial No. 5,390.

To all whom it may concern:

Be it known that I, LIONEL H. N. LOUPRET, a citizen of the United States, residing at Lowell, in the county of Middlesex and 5 State of Massachusetts, have invented certain new and useful Improvements in Magnetos, of which the following is a specification, reference being had therein to the accompanying drawings.

10 My invention relates to high tension magnetos; and its principal object is the provision of means whereby the magneto may operate successfully whether the engine rotates the armature of the magneto either 15 forward or back; the magneto becoming what may be called a reversible magneto.

My invention is particularly well adapted for use with two-cycle internal combustion engines, as for motor boats, and the like, 20 where the engine is required to be driven in one direction to move the boat ahead, and oppositely to cause the boat to go astern.

One feature of my said invention may be said to reside in a cam mounted in a breaker-box that may, by adjustment, when the engine is driving the armature in one direction or one opposite thereto, cause the seasonable engagement of the cam and the make-and-break mechanism, for the purpose of advancing or retarding the interruption of the electrical current, and hence the formation of an ignition spark, or for the purpose of stopping the engine, by rendering the magneto a non-effective spark producer.

35 A further feature of my invention is embodied in the pole-pieces of the armature and of the magnet, whose adjacent surfaces have a substantially common curvature, while the length of the chord or line connecting the ends of the arc of the end surfaces of the pole-piece of the armature is less than the shortest distance between the pole-pieces of the magnet; that is each pole-piece of the armature must not overlap both 40 pole-pieces of the magnet, if it does the magneto is not reversible.

In the drawings illustrating the principle of my invention and the best mode now known to me of embodying the same in operative structure,

Figures 1 and 2 are end elevations of my invention, in two of the various positions it may assume as shown in the diagrammatic views mentioned hereinafter.

55 Fig. 3 is a side elevation of what appears in Fig. 1, while

Fig. 4 shows a perspective view of a breaker-box, with cam affixed therein.

Figs. 5, 5^a; 6, 6^a; 7, 7^a; 8, 8^a show various relative simultaneous positions assumed respectively by the cam and interrupting device, and armature and pole pieces of the magnet.

Fixed to and rotating with the armature shaft is a plate 1 Figs. 1 and 2, upon which are mounted a make-and-break lever 2 pivoted at 3, and an adjustable contact screw 4 to contact with the lever; a spring 5 tending to keep the screw 4 and the lever 2 in engagement.

To operate the lever, when the armature 6, see Figs. 5 to 8^a inclusive, bears certain relations to the field of the magnet is a cam-member 10 with oppositely inclined end faces 11, 12, and fixed to the inside of a make-and-break casing 13 which is in frictional engagement with a suitable bearing upon the frame 14 of the generator, and concentric with the longitudinal axis 6^a of the armature 6. This casing 13 has a handle 15 whereby it may be moved, say 90 degrees, to the right or left of a vertical position, this movement being determined and limited by the sides and the ends of a slot 16, Figs. 3 and 4, in the casing, and an abutment 17 therefor in the frame 14. As the primary electrical circuit, if the magneto is to be reversible, must be broken once for each revolution of the armature, in either direction, and preferably when it bears the proper angularity to the pole-pieces 18 of the magnet, say as shown in the diagrammatic views, the cam-piece 10 is made of such length that when one end cam surface as 11 for opening the circuit, is in proper position for so opening the circuit when the armature is revolving in one direction, the other end cam surface 12 at the opposite end of the cam-piece, not only permits the timely closing of the make-and-break lever 2, of the primary circuit, before it is again opened; but, when the armature is to be rotated in an opposite direction, may be properly positioned to cause the make-and-break lever to break the primary circuit when the armature bears the proper angularity with the magnetic field of the magnet; the other cam as 11, which previously served to open the primary circuit, now serving to close it.

It is to be noted that the chord 19, Fig. 5^a, of the arc of the armature pole surface is, in length, less than the distance between the

pole-pieces 18 of the magnet, and must always be less, or in other words, the pole pieces of the field do not overlap the limiting radii, as 20, 21, of the armature 6.

5 A reference to Figs. 5 to 8^a inclusive will make plain the disposition and the certainty of operation of the various coöperating parts. When the handle 15, Fig. 5, controlling the breaker-box and hence the operating 10 cam surfaces 11, 12, is in the position at the right, the armature 6, Fig. 5^a, must rotate to the left, as indicated by the arrow; and the primary circuit will, when the armature and pole pieces of the magnet bear the relations shown in Fig. 5^a, be broken by the engagement of the cam surface 11 with the make-and-break lever 2, indicated by roll 2, the spark formed being most advanced, but if the lever be moved still more toward the 15 left until it assumes the position indicated in Fig. 6, the armature 6, Fig. 6^a, will assume a less effective position for the cam to cause the lever to break the circuit, and the spark will be retarded; so that substantially within 20 these limits of movement of the cam-piece 10, may the circuit be broken while the armature is rotating in one direction. Now if the handle 15 be given an upright position, the 25 spark will be so retarded that the engine will stop. Should the handle 15 be removed to the left from this upright position, and the armature be caused to rotate in the opposite direction, as shown in Fig. 7^a, the other cam surface 12 moves into a position to break 30 the primary circuit, that is to a retarded position; but if the handle 15 be moved still 35 farther to the left, to a position shown in Fig. 8, the armature 6, Fig. 8^a, would assume and occupy an advanced position in relation to 40 the poles of the magnet, when the cam 12 engages the break lever 2 and thus opens the circuit.

Should the handle 15 be moved into a horizontal position either to the right or 45 the left of the vertical, substantially no spark would be formed by virtue of the relative position of the armature to the field of the magnet.

In fine, I have provided means whereby the electric spark may be generated by the 50 magneto, be advanced, or retarded, or be rendered ineffective, while the armature of the magneto is driven forward or back by the engine.

Desiring to protect my invention in the 55 broadest manner legally possible,

What I claim is:

1. In a high tension magneto, make and break lever of an interrupting device fixed to and rotating with the armature shaft; a 60 cam piece adjustably mounted upon frame of magneto and concentric with a longitudinal axis of the armature, said cam piece to have three cams in one continuous surface, one concentric with the axis of the armature 65 to hold the interrupting device open, and the other two, end cams, seasonably to open and close said device, once for each revolution of the armature in either direction.

2. In a reversible high tension magneto, a 70 make and break lever of an interrupting device fixed to and rotating with the armature shaft; a cam piece adjustably mounted upon the frame of magneto and concentric with the longitudinal axis of the armature, said 75 cam piece to have three cams in one continuous surface, one concentric with the axis to hold interrupting device open, and the other two, end cams, seasonably to open and close said device, once for each revolution of 80 the armature, in either direction; and an armature each of whose pole pieces is, in width, less than the distance between the pole pieces of the magnet.

3. In a reversible high-tension magneto, 85 armature pole pieces whose chord of the arc of the pole surface, is, in length, less than the shortest distance between the pole pieces of the field.

In testimony whereof I hereunto affix my 90 signature in the presence of two witnesses.

LIONEL H. N. LOUPRET.
